SELF-CONTAINED AIR CONDITIONING UNIT

Anton F. Eilers, Evansville, Ind., assignor to Servel, Inc.,
New York, N. Y., a corporation of Delaware

Application November 12, 1953, Serial No. 391,455

9 Claims. (Cl. 62—129)

The present invention relates to air conditioning and more particularly to a self-contained air conditioning unit for a room or like enclosure.

One of the objects of the present invention is to provide an air conditioning unit of the type indicated which may be selectively adjusted to add fresh makeup air or exhaust stale room air through a single passageway.

Another object is to provide an air conditioner of the type indicated having a control damper for either directing outside air to the suction side of a fan for circulating room air over a heat absorbing element or directing room air to the suction side of a fan for circulating outside air over a heat dissipating element.

Still another object is to provide an air conditioner of the type indicated having separate compartments in which room air and outside air is circulated, a passageway communicating with the separate compartments and a damper for either closing the passageway between compartments or causing air to flow in either one or the other of two directions through the passageway.

These and other objects will become more apparent from the following description and drawing in which like reference characters denote like parts throughout the several views. It is to be expressly understood, however, that the drawing is for the purpose of illustration only and not a definition of the limitation of the invention, reference being had for this purpose to the appended claims. In the drawing:

Fig. 1 is a sectional plan view of a window type air conditioning unit incorporating the present invention and showing the rotatable damper adjusted to close the passageway between compartments;

Fig. 2 is a partial sectional view of the passageway showing the damper adjusted to direct outside air into the room;

Fig. 3 is a view similar to Fig. 2 showing the damper adjusted to exhaust stale room air through the passageway to the exterior of the room;

Fig. 4 is an extended view of the damper showing the ported casing and shutter rotatable therein; and

Fig. 5 is a sectional view taken on line 5—5 of Fig. 1 showing the passageway and damper in side elevation and manually operated knob for rotating the shutter relative to the ported casing.

The present invention may be applied to any conventional type of self-contained room air conditioning unit. For purposes of description, the invention is shown applied to a window type air conditioner which is illustrated more or less diagrammatically as the detailed construction may take other forms. The embodiment of air conditioner illustrated in Fig. 1 comprises a housing 10 adapted to be mounted in a window or other opening 11 in a wall 12 of the enclosure or room to be conditioned and has an inner portion 10a projecting into the enclosure and an outer portion 10b projecting outwardly from the enclosure. The housing 10 has spaced parallel side walls 13 and 14 and parallel front and rear walls 15 and 16. The interior of the housing is divided by a transverse

2

wall 17 into separate compartments 18 and 19 contained generally in the inner portion 10a and outer portion 10b of the housing, respectively.

An air circulating means is provided in each compartment illustrated in the form of a centrifugal type fan 20 in compartment 18 and a propellor type fan 21 in compartment 19. Fans 20 and 21 are operated by a single motor 22 having a shaft at one side extending through transverse wall 17 and connected to the rotor of fan 20 and a shaft at its opposite side mounting the fan 21.

A refrigeration system is provided in the air conditioning unit comprising a heat absorbing element or evaporator 23 mounted in compartment 18 and a heat dissipating element or condenser 24 mounted in compartment 19. A refrigerant compressor 25 is mounted in compartment 19 and preferably is of the type comprising the compressor and a driving motor enclosed in a hermetically sealed casing. Although not shown, the evaporator 23, condenser 24 and compressor 25 are suitably connected in a conventional manner to provide a refrigeration system. A filter 33 is shown mounted in the housing 10 at the front of the cooling element or evaporator 23 for removing dust or other solid particles from the air.

Each of the compartments 18 and 19 has an air inlet and an air outlet through which room air and outside air is circulated. The air inlet to compartment 18 comprises an opening 26 in the front wall 15 of the housing 10 through which room air may flow throughout the width of the filter 33 and heat absorbing element 23 to the suction inlet at the axis of the fan 20. The outlet from compartment 18 comprises the outlet 27 from the fan 20. It will be understood that the inlet and outlet to and from the fan 20 are segregated from each other as by means of a horizontal wall 28 overlying the air inlet 26 and evaporator or cooling element 23. The outlet 27 from fan 20 may discharge air through the top of the housing, not shown, or through an outlet opening in the front wall 15 of the housing above the horizontal wall 28. The air inlet to compartment 19 may comprise open louvres 29 in the side wall 13 in the outer or weather portion 10b of the housing and an air inlet port 30 in the wall 14 at the rear of the transverse wall 17, as later explained in detail. Air enters the compartment 19 through the louvres 29 and port 30 and flows toward the suction side of the fan 21. The outlet from compartment 19 comprises a centrally located opening 31 in the rear wall 16 of the housing and directly at the rear of the heat dissipating element or condenser 24. The outlet opening 31 is of substantially the same size as the condenser 24 and air from fan 21 flows through the condenser and outlet opening to the atmosphere at the exterior of the room or enclosure being conditioned. To insure a flow of air around the compressor 25 as it flows toward the fan 21 and a distribution of the air over the condenser 24, a shroud 32 surrounds the fan 21 and condenser in the compartment 19. As thus far described, the air conditioner may be considered as a conventional type in which room air is circulated in contact with a cooling element and outside air is circulated in contact with a heat dissipating element or condenser.

In accordance with the present invention, a passageway 35 is provided in the housing 10 through which outside fresh air may be supplied to or stale air exhausted from the room or enclosure being conditioned. The flow of outside fresh air or inside stale air through the passageway 35 in either one or the other of two directions is controlled by a damper 36 for either closing the passageway between compartments or opening the passageway and connecting it to the air inlet to one or the other of the compartments 18 and 19.

The passageway 35 is illustrated at one side of the

compartments 18 and 19 and formed between the side wall 14 and a parallel side wall 37 of the housing 10. The rearward end of the passageway 35 is in open communication with the atmosphere at the exterior of the enclosure being conditioned and the opposite end of the passageway is in open communication with the room adjacent the air inlet 26 to compartment 18. Port 30 in side wall 14 also opens into the passageway 35 intermediate its ends. Thus, the passageway 35 communicates with air inlets 26 and 30 to compartments 18 and 19, and provides a path for the flow of outside air into the room adjacent the air inlet 26 to compartment 18, or the flow of stale room air to the exterior of the room through the air inlet port 30 to compartment 19.

The damper 36 comprises a ported casing 40 of generally cylindrical contour extending across the passageway 35 throughout its height, see Figs. 1 and 5. The casing 40 has comparatively short cylindrical bands 41 and 42 at its top and bottom and arcuate walls 43, 44 and 45 extending vertically between the cylindrical bands 41 and 42. Arcuate wall 43 is of the greatest width and lies adjacent the wall 37 of the housing 10. The narrow arcuate strip 44 is located adjacent to and contacts the juncture of side wall 14 and transverse wall 17 at one side of the inlet port 30 to compartment 19 and narrow arcuate strip 45 lies adjacent to and contacts the end of wall 14 at the opposite side of the air inlet port 30. The bottom of the casing 40 seats on a bottom wall or base 46 of the housing 10 and the upper end of the casing underlies a top wall 47 of the housing. When casing 40 is mounted in passageway 35 the arcuate walls 43, 44 and 45 provide right angularly positioned openings or ports 48a, 48b and 48c of equal arcuate extent with the ports 48a and 48c in alignment with the passageway and port 48b in alignment with the port opening 30 to compartment 19. Mounted to rotate in the casing 40 is a shutter 50 having circular discs 51 and 52 at the top and bottom and an arcuate wall 53 extending between the top and bottom discs. To add rigidity to the shutter structure and counterbalance the arcuate wall 53, rods 54 and 55 extend between the top and bottom discs 51 and 52 at the side opposite the arcuate wall. The circular discs 51 and 52 closely fit the cylindrical bands 41 and 42 of the casing 40 to guide the rotation of the shutter 50 and the arcuate wall 53 is of a width to close a port opening 48a, 48b or 48c in the casing 40. A shaft 56 is rigidly connected with the upper disc 51 of shutter 50 at the axis thereof and projects upwardly through the top wall 47 of the housing with a knob 58 on its projecting end for manually rotating the shutter 50 relative to the casing 40. Preferably, a collar 59 is provided on the shaft 56 to hold the shutter 50 from longitudinal movement relative to the casing 40. One form of the invention having now been described in detail, the mode of operation is explained as follows.

When maximum cooling of the air in the room is desired, the shutter 50 of damper 36 is rotated relative to the casing 40 to the position shown in Fig. 1 to cause the wall 53 of the shutter to overlie the port opening 48a. The damper 36 then closes the passageway 35 between compartments 18 and 19 forwardly of the air inlet port 30 to compartment 19. With the refrigeration compressor 25 and fan motor 22 in operation, air in the room or enclosure to be conditioned is drawn through the air inlet opening 26, filter 33 and cooling element or evaporator 23 by the fan 20. The cooled air is then discharged by the fan 20 through the outlet 27 back into the room. Simultaneously, outside air is drawn into compartment 19 through the louvres 29 and also through the passageway 35 and port 30 by the fan 21. Air entering compartment 19 through louvres 29 and port 30 flows inwardly toward the fan 21 and is discharged outwardly over the heat dissipating element or condenser 24 and outlet opening 31 back to the atmosphere outside the

enclosure. Thus, the heat absorbed from the room air by the evaporator 23 at low temperature is discharged to the atmosphere at the exterior of the room at high temperature. Under these conditions of operation the air conditioner will operate to cool the air in the room at maximum capacity.

When it is desired to add fresh outside air to the enclosure being conditioned, the air conditioner is adjusted by actuating knob 58 to turn the shutter 50 relative to the casing 40 from the position illustrated in Fig. 1 to that illustrated in Fig. 2. The arcuate wall 53 of the shutter 50 then closes the port opening 48b in casing 40 and air inlet port 30 and opens the passageway 35 through the aligned port openings 48a and 48c in the casing.

Outside fresh air is then caused to flow through the passageway 35 to the interior of the room due to the communication of the inner end of the passageway with the suction side of the fan 20. The fan 20 draws room air and a certain proportion of outside air from the passageway through the air inlet opening 26, filter 33 and cooling element 23 to the fan and is then discharged by the fan back into the room. Usually fresh makeup air is added when some cooling is necessary but the maximum cooling capacity of the unit is not required.

When the recirculated air in the enclosure becomes stale or is contaminated with odors from cooking, tobacco or the like, the air conditioner may be adjusted to exhaust stale air from the room by actuating the knob 58 to turn the shutter 50 from the position illustrated in Fig. 2 to that illustrated in Fig. 3. The arcuate wall 53 then overlies the port opening 48c in casing 40 to close the passageway 35 at the opposite side of the port opening 30 from that illustrated in Fig. 1. The inner end of passageway 35 in open communication with the room, is then connected to the air inlet opening 30 to compartment 19 at the suction side of the fan 21. Due to the construction and the relative suction produced by the two fans 20 and 21, room air is caused to flow outwardly through the passageway 35 and port 30 into compartment 19 where it is discharged by the fan 21 at the exterior of the enclosure. Operation of the air conditioner with this position of adjustment is continued until the stale or odoriferous air in the enclosure has been exhausted.

It will now be observed that the present invention provides an air conditioning unit which may be adjusted to either add makeup air or exhaust stale room air through a single passageway. It will further be observed that the present invention provides a damper for either closing the passageway between compartments or opening the passageway to cause flow of room air or outside air in either one or the other of two directions therethrough. It will also be observed that the present invention provides a construction and arrangement of elements for directing outside air to the suction side of a fan for circulating room air or directing room air to the suction side of a fan for circulating outside air.

While a single embodiment of the invention is herein illustrated and described, it will be understood that modifications may be made in the construction and arrangement of elements without departing from the spirit or scope of the invention. Therefore, without limitation in this respect, the invention is defined by the following claims.

I claim:

1. In an air conditioner of the type having a compartment with a heat absorbing element therein, a compartment with a heat dissipating element therein, an air inlet and outlet to and from each compartment, air circulating means for circulating air from an enclosure to be cooled and ambient air from outside the enclosure through the compartments having a heat absorbing and heat dissipating element, respectively, the combination with such an air conditioner of selective means for independently exhausting stale air from or adding outside ambient air to the enclosure comprising an open passageway communicat-

cating with the enclosure and the outside ambient, said passageway having ports communicating with the separate compartments at the suction side of the air circulating means, and a single movable damper mounted in the passageway to either close the port from the passageway to the compartment having the heat dissipating element and open the passageway or open said port and close the passageway between said port and the outside ambient.

2. An air conditioner in accordance with claim 1 in which the single movable damper is mounted in the passageway to close the port from the passageway to the compartment having the heat dissipating element or close the passageway on either side of said port.

3. An air conditioner in accordance with claim 1 in which the single movable damper is mounted to close the passageway between ports in one position, close the port from the passageway to the compartment having the heat dissipating element in another position to cause outside air to flow in one direction through the passageway to the suction side of the compartment having the heat absorbing element, or close the passageway between said port to the compartment having the heat dissipating element and the outside ambient in another position to cause air from the enclosure to flow in the opposite direction through the passageway and port to the suction side of said compartment.

4. An air conditioner in accordance with claim 1 in which said port from the passageway to the compartment having the heat dissipating element constitutes an outside air inlet and the passageway constitutes a bypass around said port to the air inlet to the other compartment when said port is closed by said damper.

5. An air conditioner in accordance with claim 1 in which the passageway constitutes a bypass around the air inlet to the compartment having the heat absorbing element when said damper is adjusted to open the port from the passageway to the compartment having the heat dissipating element and close the passageway between said port and the outside ambient.

6. An air conditioner in accordance with claim 1 in which the damper is in the form of an arcuate shutter and mounted to rotate to different angular positions in the passageway.

7. An air conditioner in accordance with claim 1 in which the passageway is of rectangular cross section, the port to the compartment having the heat dissipating element is an opening in the side wall of the passageway, and the damper comprises a generally cylindrical casing mounted vertically in the rectangular passageway and

having three angularly related spaced openings in alignment with the passageway and port opening to the compartment having the heat dissipating element, an arcuate shutter rotatably mounted in the casing for closing any one of the three openings in the casing, and means for rotating the shutter relative to the casing.

8. In a room air conditioner of the type having a compartment with a heat absorbing element therein through which a stream of room air is circulated in a predetermined path and an adjacent compartment with a heat dissipating element therein through which a stream of outside air is circulated in a predetermined path, the combination with such a room air conditioner of a port opening between the compartments, a single damper for closing the port opening in one position and movable to a plurality of other positions, and said port opening and damper being so constructed and arranged with respect to the paths of the air streams in the different compartments as to induce the flow of outside air through the port opening into the room in one of said plurality of positions and induce the flow of room air through the port opening to the outside in another of said plurality of positions.

9. An air conditioner having a housing divided into adjacent compartments, a refrigeration system having a heat absorbing element in one compartment and a heat dissipating element in the adjacent compartment, each of said compartments having an air inlet and outlet, means for circulating room air and outside air through the respective compartments, a passageway between compartments, a damper having at least one vane for closing the passageway and movable to a plurality of other positions, said damper in one of said plurality of other positions opening a path from the air inlet to one compartment to the passageway and baffling the flow of air from the passageway to the outlet from said compartment, and said damper in another of said plurality of other positions closing the path from the air inlet to the passageway and opening a second path from said passageway to the air outlet from said compartment.
